HEAT SINK FOR A TRANSISTOR

Raymond C. Root, Columbus, Nebr., assignor to Richleu Corporation, Columbus, Nebr., a corporation of Nebraska

Filed Feb. 4, 1964, Ser. No. 78,504

Term of patent 14 years

(Cl. D26—1)

FIG. 1

FIG. 2

FIG. 3

FIG. 4

FIGURE 1 is a perspective view of a heat sink for a transistor, showing my new design.

FIGURE 2 is a front elevational view, the rear being substantially a mirror image thereof.

FIGURE 3 is a side elevational view, the opposite side being substantially a mirror image thereof.

FIGURE 4 is a bottom plan view, the top being substantially a mirror image thereof.

I claim:

The ornamental design for a heat sink for a transistor, as shown and described.
